UNITED STATES PATENT OFFICE.

ULYSSES GRANT HOUSTON, OF PARVIN, OKLAHOMA TERRITORY.

ASTRONOMICAL APPARATUS OR PLANETARIUM.

SPECIFICATION forming part of Letters Patent No. 770,370, dated September 20, 1904.

Application filed June 27, 1903. Serial No. 163,406. (No model.)

To all whom it may concern:

Be it known that I, ULYSSES GRANT HOU-
TON, a citizen of the United States, and a resi-
dent of Parvin, county of Kingfisher, Okla-
homa Territory, have invented new and use-
ful Improvements in Astronomical Apparatus
or Planetariums, of which the following is a
specification, reference being had to the ac-
companying drawings, two sheets illustrating
the invention, in which—

Figure 1 is a perspective view of an appa-
ratus embodying my invention. Fig. 2 is a
vertical longitudinal section thereof. Fig. 3
is a rear view of the actuating-arm and coact-
ing parts, as hereinafter explained.

The purpose of this invention is to provide
an astronomical apparatus or planetarium
which will enable the teacher to mechanically
demonstrate to the pupil that the earth's sea-
sons or those of other planets are dependent
not only upon the obliquity of the earth's axis
to the plane of its orbit at a fixed angle in its
orbital movement about the sun or other cen-
tral luminary, but also upon the constant par-
allelism of the earth's axis to itself in the vari-
ous positions during its orbital movement and
upon the maintenance by the force of gravity
of said axis in a true line pointing toward the
north star throughout the entire revolution of
the planet about the central luminary.

The mechanism employed is as follows:

A represents a casing having a hollow in-
terior and a central enlarged opening, such
casing being here shown formed in truncated
oval form similar to the case of the common
mantel-clock and adapted to be supported or
suspended in vertical position normally.

B represents the operating mechanism as a
whole mounted in and upon said casing.

C represents the gravity-weight, actuating-
arm, and locking-slide as a whole detached.

a indicates near the top of the face of the
casing the north star, toward which the axis
of the earth always points in space, which is
here symbolized by the inclination of the axis
t of the planet toward that point or upper
part of the casing, as a, where the north star
is diagrammatically represented.

b is the pointer end of the horizontal actu-
ating-arm h and indicates the months d and

signs of the zodiac c, all of which are grouped
concentrically around the enlarged opening in
the casing and toward which the index points
as the arm is swung round to operate the de-
vice.

55

e represents the earth or other planet, sup-
ported upon an inclined axis t, rotating in and
swiveled through the auxiliary regulating-
weight i.

f represents the central luminary, supported
upon a vertical axis o, which last rests in a
socket in or is otherwise secured to the pillar
p, fastened to the bottom of the casing.

g represents a satellite—as, for example,
the moon, which revolves twelve and one-third
times around the planet during the year—
which representation of the satellite is sup-
ported upon a vertical axis j, fastened to the
interiorly-toothed horizontal gear k and here
shown as bent toward its lower end and sock-
eted into the side of the said gear.

h is the actuating-arm, journaled upon the
axis o and resting on the pillar p.

i is the auxiliary regulating-weight, mount-
ed eccentrically upon the vertical journal-rod
y and here shown as fastened rigidly thereto
by means of a thumb-screw taking through
the weight and against the said rod, which
rod carries at its lower end the gravity-weight
n, secured eccentrically thereto.

80

k is the interiorly-toothed horizontal gear
here shown as cup-shaped with teeth upon its
interior perimeter and fastened by a thumb-
screw or otherwise to the sleeve-axis x and
resting upon the actuating-arm, said gear 85
meshing with a pinion r, attached rigidly to
the inclined axis t.

l is the horizontal locking-slide having an
elongated slot v therein, through which last
takes the axis o, said slide having at its inner 90
end a projection u, adapted to fit into either
of the recesses s upon the disk m, and thereby
lock the mechanism against gravity control,
and said slide having preferably upturned
longitudinal edges fitting against the sides of
the actuating-arm, beneath which last said
slide is constructed and arranged to move.

95

t' indicates a thumb-piece for operating the
slide. Such thumb-piece, which forms no
essential part of my invention, may be em- 100

ployed for convenience in operating the locking-slide and may be constructed in the usual conventional form, as shown.

The disk m is rigidly secured upon the 5 gravity-weight n and to journal-rod y .

q is a perforated ribbon or band secured and fitting tightly in the enlarged opening of the casing, said perforations adapted to coact with the pins or teeth upon gear w , which 10 last is formed upon the sleeve-axis x , and so through the gear k and the pinion r to produce the rotation of the planet and the revolution of the satellite.

z is the aperture in the farther end of the 15 actuating-arm h , through which passes the sleeve-axis x with the vertical journal-rod y .

It will be observed that when the apparatus is positioned upright or vertically and the locking-slide not applied the gravity-weight, 20 assisted by the auxiliary regulating-weight, maintains the axis of the planet turned always toward the north star in space, here symbolized by the inclination of the axis t of the planet toward that point or upper part of 25 the casing, as a , where the north star is diagrammatically represented, and so as the actuating-arm is swung around, carrying the planet in its annual revolution, now receding from and now approaching the central luminary, demonstrating mechanically the natural 30 change in the seasons, the inclination of the planet's axis to the plane of its orbit contributing to produce the said effect. When the locking-slide is pushed forward, causing 35 the projection u to enter the recesses s in the disk m , and so to lock the gravity-weight in either of two positions, as shown, it will be seen that though the inclination of the planet's axis remains the same the natural change 40 of seasons does not follow; but according as the gravity-weight is locked a full year of summer or winter is given to either hemisphere, as desired. When the device is positioned horizontally and the locking-slide not 45 applied, the operation of the apparatus will illustrate catastrophic and abrupt alterations in climate.

Diagrammed upon the face of the casing

are illustrated the orbital movement of the planet and the consequent change of seasons 5° d' , the phases of the moon as affecting the tides f' , and the parallels and meridians of the planet e' . These last features form no necessary part of my invention, but are valuable educational ancillaries to the device. 55

Reserving to myself the benefit of the full range of mechanical equivalents in the detail construction and arrangement of parts and having thus described my invention, what I claim, and desire to secure by Letters Pat- 60 ent, is—

1. In a device of the character described and in combination, means for representing a central luminary, means for representing a planet, actuating mechanism connecting the two, and gravity means attached to the planet means, whereby as the actuating mechanism is operated the force of gravity maintains the axis of the planet always inclined toward a fixed point upon the casing wherein the device is 7c mounted, such point diagrammatically representing the north star as the orbital movement is described.

2. In a device of the character described and in combination, means for representing a central luminary, means for representing a planet, actuating mechanism connecting the two, gravity means attached to the planet means, and locking means attached to the actuating mechanism and adapted to coact with the gravity 8 means, whereby as the actuating mechanism is operated the force of gravity acts, or is locked against acting as desired, to maintain the axis of the planet always turned toward a fixed outside point such as the north star as 8 the orbital movement is described, or to hold said axis turned toward or away from the central luminary, according as the locking means be applied or not applied.

In witness whereof I have hereunto sub- 9 scribed my name this 27th day of June, 1903.

ULYSSES GRANT HOUSTON.
